(57) **CLAIM**

The ornamental design for a desk, as shown and described.

DESCRIPTION

FIG. 1 is a perspective view of a desk showing my new design;

FIG. 2 is a front view thereof;

FIG. 3 is a rear view thereof;

FIG. 4 is a right side view thereof, the left side view thereof being a mirror image;

FIG. 5 is a top view thereof;

FIG. 6 is a bottom view thereof;

FIG. 7 is a cross sectional view thereof taken along line 7-7 in FIG. 2, where the internal mechanism is omitted;

FIG. 8 is an enlarged view of the portion indicated by line 8 in FIG. 7; and,

FIG. 9 is an enlarged view of the portion indicated by line 9 in FIG. 1.

The broken lines in figures are for the purpose of illustrating portions of the desk and form no part of the claimed design.

1 Claim, 5 Drawing Sheets
